PHONOGRAPH RECORD CHANGER

Joseph Erwood and John Erwood, Chicago, Ill.,
assignors to The Erwood Co., Chicago, Ill., a
corporation of Illinois

Application November 20, 1944, Serial No. 564,210

15 Claims. (Cl. 274—10)

This invention relates, in general, to intermittent feed mechanism, and has more particular reference to mechanism adapted to deliver phonograph records successively in operating position in record playing apparatus, that is to say, the invention specifically pertains to phonographic record changing apparatus.

Automatic record changing apparatus normally comprises the combination, with a motor driven record turntable and tone pickup arm movable over the turntable, of means for supporting a stack of records and for delivering records, one by one, from the stack to the turntable, and means for raising and lowering, and swinging the tone arm, at properly timed intervals, to apply the same to a record to be played, to retract the same from the record at the conclusion of the record playing operation, and to swing the tone arm to a position allowing a succeeding record to be deposited in playing position on the turntable. Apparatus hitherto provided for record changing purposes has been of relatively complex nature, embodying many parts forming more or less intricate mechanism, the same being expensive to make and assemble, requiring accurate adjustment, and being apt to get out of order.

As exemplified in United States Letters Patent No. 2,230,106, issued to one of the joint inventors hereof under date of January 28, 1941, it has heretofore been proposed to improve and simplify automatic record changing apparatus with some success. Presently, however, we seek to provide still further improvement and simplification, and an important object of the present invention is to provide apparatus of utmost simplicity, comprising a minimum number of rugged parts that are easy to make and assemble whereby to provide low cost record changing apparatus having improved service qualities and requiring minimum adjustment and care in operation.

Another important object is to provide record changing mechanism that is held in cocked, yet inactive condition, thus eliminating operational noise, while the record is being played, the mechanism becoming active to perform its record changing cycle, automatically, at the conclusion of the playing of a record, and also being manually releasable at any time, for record changing purposes, as during the playing of an unwanted record.

Another important object is to drive the record changing mechanism by cam means, in turn driven by the turntable motor; a further object being to form the cam directly on the record turntable, thereby eliminating an extra part.

Still another important object of the invention is to utilize a cam of spiral configuration and to drive the record change mechanism by causing a cam follower, connected thereto, to ride the spiral cam between the outer and inner portions thereof; a further object being to utilize a pair of cam followers adapted alternately to ride the cam and thus move the mechanism successively in opposite directions in performing its record changing cycle and returning to an inactive, starting position in which it is cocked and ready for a repeat performance.

Another important object is to employ the movement of the cam following mechanism, in one direction, to lift and return the tone arm to an inactive or starting position and to then perform a record change operation, and to employ the movement of the mechanism, in the return direction, to swing and deposit the tone arm, in playing position, on the changed record and to latch the change mechanism in cocked position ready upon demand to repeat its operational cycle.

Another important object is to drive the change mechanism, in one direction, by the cam, upon release of a cam follower from cocked and latched position, the cam being formed to recock and latch the follower in retracted inoperative position at the conclusion of mechanism movement in one direction, another cam follower being then released from cocked and latched position to cooperate with the cam to return the mechanism to starting position, the cam serving to recock and relatch the said other follower when the change mechanism reaches such starting position.

Another object is to provide simple means actuated by cam driven change mechanism for raising, lowering and swinging the tone arm; a further object being to raise and lower the arm by means of a cam on the change mechanism and to swing the arm by a friction wheel.

Another object is to provide a manually adjustable stop projectable to various selected positions for determining the tone arm position at the commencement of a record playing cycle whereby the device may be conditioned for playing records of various size; a further object being to accomplish the projection and retraction of said stop, as by a cam on the change mechanism, a further object being to provide for releasing the tone arm from said stop by retraction of the stop after playing position of said arm has been determined, whereby the arm may then move freely over the turntable in playing a record.

Another object is to provide manually operable means for locking the change mechanism in

cocked, inoperative position and to disable said tone arm stop in retracted position whereby the apparatus may function as if not provided with record changing mechanism.

Another object is to provide a common control, preferably a knob or handle turnable at will to several selective positions, in one of which the change mechanism is latched against operation and in others of which the mechanism is released for operation on records of various size.

Another object is to provide a control, preferably in the form of a push button, manually operable to release the change mechanism for operation during the playing of a record so that the record may be rejected and changed at will; a further object being to combine the reject button with the record size adjusting knob by disposing the button centrally of the knob to provide a neat unitary control for the entire mechanism.

Another object is to provide improved latch tripping means for releasing the change mechanism for operation, when the tone arm reaches the limit of its record playing movement, and also if the arm, before reaching such limit, should receive a rocking movement, such as may be applied thereto upon contact with an eccentric record groove, of the type applied in most records, at the termination of the playing grooves therein, the latch tripping means being also operable at will by the manually operable reject button.

The foregoing and numerous other important objects, advantages and inherent functions of the invention will become more apparent as the same is more fully understood from the following description, which, taken with the accompanying drawings, discloses a preferred embodiment selected for the purpose of demonstrating the invention.

Referring to the drawings:

Fig. 1 is a perspective view of a phonographic record player embodying the present invention;

Fig. 2 is a perspective view of the underside of a record turntable forming part of the device shown in Fig. 1;

Fig. 3 is a perspective view of the device shown in Fig. 1, with the turntable removed;

Fig. 4 is a plan view of the underside of the apparatus shown in Fig. 3, the record changing mechanism being shown in the position occupied during the record playing operation and at the commencement of the record changing cycle;

Fig. 5 is a view, similar to Fig. 4, showing the apparatus in position midway through the record changing cycle;

Fig. 6 is an enlarged view of a portion of the apparatus shown in Figs. 4 and 5;

Fig. 7 is a sectional view taken substantially along the line 7-7 in Fig. 6.

Fig. 8 is a sectional view taken substantially along the line 8-8 in Fig. 6;

Fig. 9 is a partial side elevational view;

Fig. 10 is a sectional view taken substantially along the line 10-10 in Fig. 9; and

Fig. 11 is a side view of the control device shown in Fig. 9.

To illustrate the invention, the drawings show a record player 11 comprising a support plate 13 carrying a record turntable 15 mounted for rotation thereon about the axis of a central stem 17, the turntable being driven by a preferably electric motor 19, which is preferably supported by and at the underside of the plate 13, the motor being drivingly connected with a turntable driving wheel 21, which preferably extends upwardly of the plate 13 and forms frictional driving con-

nexion with a groove 23 formed at the peripheral edge of the turntable 15. The plate 13 carries a pedestal 25, outwardly of the edge of the turntable, on which pedestal is supported a tone pickup arm 27, which is pivoted for movement about the vertical axis of the pedestal and also for movement about a horizontal axis whereby the pickup device, on the arm 27 at the end thereof remote from the pedestal 25, may be applied to and lifted from the turntable, and a record thereon, and may swing horizontally across the turntable.

It will be understood, of course, that the pickup device on the arm 27 may be connected with suitable sound reproducing equipment so that by applying the pickup device to a record on the turntable and by energizing the motor to operate the turntable, to thus rotate the record beneath and against the pickup device, a sound recording on the record may be reproduced at the apparatus with which the pickup device is connected.

In order to provide for the automatic delivery of records successively on the turntable in position to be engaged and played by the pickup device on the arm 27, we have provided, on the plate 13, compact and simplified record changing apparatus including means for supporting a stack of records 29 in position, above the turntable, to be successively delivered in playing position on the turntable. To this end, the plate 13 is provided with a pair of pedestals 31 preferably arranged on diametrically opposite sides of the turntable and located outwardly of the peripheral edges thereof. These pedestals carry record supporting and changing means comprising horizontally disposed blades carried on the pedestals 31 and movable about the vertical axes of the pedestals. Each pedestal carries a record supporting blade 33 normally held in position, on the pedestal, with the end of the blade overlying and extending vertically above the peripheral edge of the turntable so that the stack 29 of records to be played may be supported, at the opposite sides of the stack, on the ends of the blades 33, with the upper end of the stem 17 projecting through the aligned central openings of the records comprising the stack 29. Each pedestal 31 also carries a record changing blade 35 extending therefrom substantially at right angles with respect to its cooperating blade 33, each blade 35 being offset upwardly of its cooperating blade 33 a distance substantially equal to the thickness of a record disc. Each blade 35 is formed with a preferably substantially knife-edged nose 37 in its side adjacent its cooperating blade 33, that is to say, the side of the blade 35 which normally extends adjacent to the record stack 29.

By causing the blades 33 and 35 to turn on the pedestals 31 in unison and in a counter-clockwise direction, viewing the apparatus, as shown in Fig. 1, from above, the blades 33 may be swung outwardly from beneath the stack 29 while the blades 35 are swung inwardly, the noses 37 of the blades 35 entering between the lowermost record of the stack and the record immediately above such lowermost record whereby said blades 35 will support and retain all of the records comprising the stack 29, except the lowermost record which, being released by the outward movements of the blades 33, may fall into playing position on the turntable under the guidance of the stem 17. By reversing the movement of the blades, the blades 35 may be retracted from stack supporting position and replaced by the stack supporting blades 33 in order to condition the record chang-

ing means for a successive performance of the record changing cycle.

In order to correlate operation of the record changing blades with the record playing movement of the arm 27 we provide simplified mechanism operable upon the completion of the playing of a record on the turntable, to first raise the tone arm from the record and swing it outwardly on the pedestal 25 to a stand-by position entirely clearing the turntable; then to cause the record changing blades to perform their record changing cycle; and, finally, to turn the arm 27 to swing inwardly and drop upon the turntable to apply the pickup device in starting position on the record to be played.

To this end, as shown more particularly in Fig. 8 of the drawings, the tone arm support pedestal 25 forms a vertical bearing for a tubular arm support 39, which is turnable within and about the vertical axis of the pedestal 25. One end of the support 39 extends at the upper end of the pedestal and carries a bracket 41 fixed thereto, the tone arm 27 being pivotally mounted on the bracket by means of a horizontal pivot pin 43. The tubular support 39 has an end extending outwardly of the pedestal 25 beneath the support plate 13, said end carrying an arm or blade 45 fixed on and extending radially of the tube 39, and a friction drive wheel 47 fixed on the tube adjacent the arm 45. Outwardly of the friction wheel 47, the end of the tube 39 may be provided with a collar 49, and a spring washer 51 may be interposed between the collar and the friction wheel.

It will be seen that the foregoing construction allows the arm 27 to swing horizontally about the vertical axis of the pedestal with the tube 39 turning within the bearing afforded by the pedestal, and that the arm 27 may swing vertically about the horizontal axis provided by the pin 43. Axially movable within the bore of the tube 39 is a pin 53, the head 55 of which extends outwardly of the tube 39 at the collar 49. The other end of the pin 53 extends outwardly of the tube 39 at the bracket 41 in position to bearingly engage a shoe 57, which is fixed on the arm 27. By controlling the position of the pin 53 in the tube 39, the elevation of the arm 27 with respect to the turntable may be determined. By pushing the pin 53 upwardly in the tube 39, the arm 27 may be swung upwardly on its pivot 43 and conversely the arm may be allowed to drop under the influence of its own weight by lowering the pin in the tube 39.

The pedestals 31, which carry the record changing blades, are preferably hollow to form vertical bearings for pins 59 upon which the record changing blades are secured. These pins 59 have ends projecting from the lower ends of the pedestals 31 beneath the support plate 13 and are fitted with radially extending arms 61, which are tied together by means of a connecting bar 63 so that the pins 59 and the record changing blades thereon may move only in unison. One of the pins 59 also has a radial driving arm 65 fixed thereto by means of which the pins may be turned.

In order to correlate the movements of the tone arm with the record changing operation of the record changing blades, the plate 13 carries an operating member 67 periodically movable under the driving influence of the motor 19 and cooperatively associated with the tone arm to raise and swing the same to stand-by position upon the completion of the playing of a record,

said operating member being also drivingly connected with the driving arm 65 by means of a connecting rod 66 to operate the record changing mechanism when the member 67 is moved. The member 67 also controls means to swing and apply the tone arm to a record deposited in playing position on the turntable by the operation of the record changing mechanism. We provide novel latch controlled mean for drivingly connecting the operating member 67 with the motor 19 at the conclusion of the playing of a record in order to initiate and to carry out the record changing cycle of operation. We also provide improved and simplified means for raising and swinging the tone arm 27 in response to movement of the operating member 67 and for determining the starting position at which the arm is deposited, by the mechanism, upon a record to be played, whereby the mechanism is instantly adjustable to operate upon records of various size, such as the ten inch and twelve inch records in common use. As a further refinement, we provide simplified means for latching and thus securing the operating member in stand-by position to thereby disable the record changing apparatus and allow the record playing mechanism to function with the automatic record changing equipment inoperative.

The operating or actuating member 67 preferably comprises a sheet metal plate having a pair of arms 69 and a central body 71, the arms 69 being formed at one end of said central body and the other end of the body being pivotally secured upon the underside of the support plate 13, as by means of a suitable pivot pin 73. Secured to the body of the operating member 67 at the pivot pin, and turntable with the body about said pin, are segmental plates 75 and 77 having circular edges 79 and 81, respectively, centering on the axis of the pivot pin 73. The edge 79 of the blade 75 frictionally engages the friction wheel 47 on the tubular tone arm support 39 and serves to rotate the support and the tone arm in response to movement of the operating member 67 about its pivot pin 73. The blade 77 is provided at its edge with a block 83 forming a cam in position to engage the head 55 of the tone arm raising pin 53 when the operating member 67 is turned on its pivot into position bringing the cam 83 into contact with the head of the stem, whereby the arm 27 may rest on the turntable at a record playing elevation so long as the head of the stem engages the edge of the blade 77; but the arm 27 will be raised from playing position whenever the head of the stem engages the cam 83.

The operating member 67 normally occupies its stand-by position illustrated in Figs. 4 and 6 of the drawings, during the playing of a record. The operating member 67 is yieldingly retained in such stand-by position, as by means of a latch member 85, which may comprise a latch blade pivotally mounted on a pin 87, and yieldingly urged on said pin as by means of a spring 89, 65 in a direction to yieldingly engage a detent 91 on the operating member 67.

The arms 69 of the operating member 67 carry selectively operable clutch devices 93 and 93' for drivingly connecting the operating member with the motor 19. As shown, the devices 93 and 93' comprise retractable pins 95 adapted to be held normally in retracted position on the arms 69 but releasable for projection to active position in which said pins may engage in and ride along 75 a cam way 97 preferably comprising a spiral

groove formed in a turntable member driven by the motor. The cam way 97 may conveniently comprise a spiral groove formed on the underside of the turntable 15, as shown more particularly in Fig. 2 of the drawings. As shown, the spiral groove extends from the outer edge of the turntable toward its central portion 100, which forms a land. The groove preferably has uniform depth throughout its length from its outer end to adjacent its inner end, but becomes shallower and provides a pin depressing incline 99 which merges with the bottom surface of the central turntable portion 100 at the inner end of the groove.

The devices 93 and 93' preferably each comprise a bushing 101 secured at one end thereof on the member 67, as by means of a holding nut 103 threaded on the bushing and clamping the same in place. The other end of the bushing extends through a curved slot formed in the plate 13. Each bushing 101 thus extends in a corresponding guide slot, the member 93 operating in a slot 105 and the member 93' operating in a slot 105'. The slots 105 and 105' are curved about the axis of the pivot pin 73 as a center and the bushings 101 have ends projecting upwardly of the plate 13 immediately beneath the turntable. The upwardly projecting ends of the bushings 101 may each carry a nut 107, but the bushings are freely movable along the guide slots 105 and 105'. Each bushing carries one of the pins 95 axially movable therein with an end of each pin exposed at the upper end of its supporting bushing. The pins also have portions extending outwardly of the lower ends of the bushings for engagement with preferably leaf springs 109 mounted on the member 67 and serving to yieldingly urge the pins in an upward direction in the bushings to project the cam engaging portions thereof toward the underside of the turntable. The pins are normally retained in retracted position against the influence of the springs 109 by means of latches 111 and 111'. These latches comprise levers pivoted, as at 113, in lateral slots 115 formed in the bushings 101, said latches normally seating in circumferential latch grooves 117 formed in the pins 95 to hold the same in retracted position. The latches are normally urged toward pin holding position by springs 119 mounted on the arms 69 adjacent the bushings 101. The levers 111 and 111', however, may be moved against the influence of the springs 119 to release the pins 95 for upward projection in the bushings 101.

The latching groove 117 of the device 93' may be formed with an inclined side 118, as shown at the left hand side of Fig. 7, to cooperate with the correspondingly formed portion of the latch 111'. This construction allows the pin 95, after it has been raised to latching position on the central land 100, by the inclined groove portion 99, to be further retracted to separate its end from the land surfaces 100 by the camming action of the latch 111' with the inclined groove side 118. To this end the spring 119, associated with the latch 111', is made adequately strong to perform its pin retracting cam action.

If desired also, the latching groove 117 of the device 93 may be made with an inclined side similar to the side 118 in the device 93' in order to retract the pin from the relatching land 100. It is desirable, however, that the spring 119, which cooperates with the latch 111, be relatively weak to permit easy hair trigger release of the latch 111 as hereinafter described. It is, therefore, de-

sirable to form the latching groove 117 in the device 93 with straight sides so that the pin 95 may be securely latched by the lever 111 under relatively light spring tension. In order that the pin 95 may clear the underside of the turntable when in latched position, the underside of the turntable outwardly of the central land 100 is cut away, as at 120, sufficiently to clear the end of the pin 95 after it has been latched by riding onto the central land 100. The device 93, as will hereinafter appear, after being latched by riding onto the land portion 100, is immediately moved outwardly thereof by the driving engagement of the device 93' in the groove 97.

15 The stem 17, upon which the turntable is turnably mounted, is preferably fixed in the plate 13, as by means of a suitable fastening nut 26, and extends upwardly of the plate, providing a bearing 121 for the turntable at the base of the stem. 20 It should be noted that the slots 105 and 105' extend on opposite sides of the pin 17 and that the devices 93 and 93', which operate in said slots, cooperate with the cam 97 on opposite sides of the pin 17. When in stand-by or starting position, the member 67 supports the device 93 at the outer end of its guide slot 105, the other device 93' being supported at the inner end of its guide slot 105'. If desired, a stop block 123 may be secured on the underside of the plate 13 at the outer end of the slot 105 to accurately determine the stand-by or starting position of the member 67 by engagement with the bushing 101, as shown more particularly in Fig. 7 of the drawings.

25 Cooperatively associated with the latch member 111, is a latch tripping lever 125 comprising a member pivotally supported on the plate 13, as by means of the pivot 127, said lever 125 having an arm 129 extending adjacent the latch member 111 and adapted to shift said latch member when the lever 125 is rotated on its pivot in a counter-clockwise direction, viewing Fig. 6, rotation of the lever in a clockwise direction being preferably limited by means of a stop pin 130 in the plate 13. The arm 45, which turns with the tone arm, being secured thereto by the sleeve 39, has an end which swings adjacent an edge of the lever 125, said arm 45 being provided with means for moving the lever 125 to release latch 111 upon the completion of the playing of a record. To this end, the lever 125, in its edge facing the swinging end of the arm 45, is provided with a series of teeth 131, while the arm 45 at its swinging end carries pivoted thereon, a tooth member 133. This tooth is connected with a relatively weak spring 135, which serves yieldingly to hold the tooth in position, projecting at the swinging end of the arm 45, to engage the teeth 131 of the lever.

30 At the commencement of the playing of a record, the arm 45 will occupy a position approximately as shown in solid lines in Fig. 6 of the drawings. During the playing of a record, the movement of the tone arm radially of the turntable will cause the arm 45 to travel in a counter-clockwise direction, viewing Fig. 6, to a position at the conclusion of the playing of a record substantially as indicated in dotted lines in Fig. 6. During such movement of the arm 45, the tooth 133 will travel along the lever 125 and across the teeth 131 therein. So long as the arm 45 travels continuously in one direction during the playing of a record, the action of the tooth 133 upon the lever 125 will be to urge it in a clockwise direction, viewing Fig. 6. Movement of the lever in such direction, however, is prevented by the pin 130.

It will be noted also that during the travel of the tooth 133 along the edge of the lever 125, the tooth 133 will be tilted on the arm 45, the spring 135 yielding to allow the tooth to so tilt. Disc records ordinarily are provided with an eccentric groove into which the pickup device is delivered at the conclusion of the playing of the sound track of a record. When the pickup device enters such eccentric record groove, the tone arm 27 and the arm 45 will be rocked back and forth. As the arm 45 moves backwardly from the position shown in dotted lines in Fig. 6, the tooth 133 will be caused to straighten itself on the arm due to the engagement thereof with the teeth 131, thereby imparting a toggle action causing the lever 125 to rotate in a direction to trip the latch lever 111. In the event that a record being played is not provided with an eccentric groove, the end of the latch lever 111 has an end fitted with an adjustable pin 137, which is supported in position such that record playing movement of the arm 45 beyond a predetermined position will trip the latch lever by direct engagement therewith.

As soon as the latch lever 111 is tripped, the pin 95 of the operating device 93 will be released and projected under the influence of the spring 109 into position to engage the outer end of the cam groove 97. Thereafter, continued rotation of the turntable will draw the device 93 radially inwardly along the slot 105 by the action of the spiral cam upon the pin 95, thereby rotating the member 67 about its pivot 73 in a counter-clockwise direction, viewing Fig. 6. Such movement will continue until the parts reach relative positions, as shown in Fig. 5. When in such position, the actuating pin 95 of the device 93 will have reached the inner end of the cam groove and rides up the inclined grooved portion 99 onto the central portions of the turntable thereby returning the pin to latched position against the influence of the spring 109.

During the initial portions of the movement of the member 67 under the driving influence of the device 93, the tone arm 27 will be raised through the engagement of the head of the pin 53 with the cam block 83 and the tone arm will have been swung outwardly of the peripheral edge of the turntable by the action of the plate 75 on the friction wheel 47, such outward movement of the tone arm being limited by a stop pin 139 positioned on the underside of the plate 13 to engage and limit the movement of the arm 45 in the limit position shown in Fig. 5 of the drawings. Thereafter, continued movement of the member 67 will actuate the record changing mechanism since the member 67 is connected therewith by means of the connecting rod 66, said rod having a slot 141 to afford lost motion connection with the member 67, whereby the record changing mechanism is not actuated during the period of initial movement of the member 67, thereby affording adequate time within which to retract the tone arm outwardly of the peripheral edge of the turntable.

The plate 13 on its underside is provided with a latch releasing stop member 143 in position to engage the latch member 111' when the actuating member 67 reaches the position shown in Fig. 5. When in such position, the member 93' is disposed opposite the peripheral portions of the turntable so that upon actuation of the latch member 111' the pin 95 of the driving member 93' will be projected to operating position by the spring 109. Continued rotation of the turntable thereafter will return the member 67 to its initial or stand-by position by the action of the driving

device 93' and its pin 95 in the cam groove 97. As the member 67 reaches its inoperative or stand-by position, the pin 95 of the device 93' will ride up the inclined inner end of the cam groove, thereby relatching the device 93' so that the member 67 will thereafter be and remain entirely disconnected from the turntable and driving motor and will be retained in stand-by position by operation of the spring latch 85 and detent 91.

- 10 During the initial portions of the returning movement of the operating member 67 from its projected position shown in Fig. 5, the tone arm will first be swung inwardly by the action of the blade 75 on the friction wheel 47 to a position determined by an adjustable stop latch 145 disposed at the underside of the plate 13 adjacent the arm 45. This latch comprises a member preferably pivoted at one end on the pin 87. The member 145 is yieldingly urged, as by means of a spring 147, in a direction to engage an adjustable stop 149. This stop may be manually adjusted on the plate 13 to several positions. The member 145 has stop shoulders 151, said shoulders being in position to engage a positioning pin 153 mounted in the arm 45, said positioning pin being adapted to engage a stop shoulder 151 selected by the position of the adjustable stop 149. In the illustrated embodiment there are two shoulders 151 so that with the member 145 in the dotted line position in Fig. 6, movement of the tone arm inwardly, during the initial portions of the return movement of the member 67, will be stopped by a shoulder 151 in a predetermined position with respect to the edge of the turntable, such position corresponding with the size of the record to be played. For this purpose, the two shoulders 151 may correspond, respectively, with a ten inch record and a twelve inch record. The member 145 also is provided with a shoulder 155 and the latch member 85 is provided with a pin 157 in position to engage the shoulder and retract member 145, as from dotted line position to solid line position shown in Fig. 6, thus retracting the stop shoulders 151 from the pin 153 and releasing the tone arm for playing movement over the record. Such retraction of the member 145 is accomplished during the latter portions of the returning movement of the member 67 to stand-by position. To this end, the member 67 is provided with a cam 159 which may incorporate the latch detent 91. This cam cooperates with the latch member 85, to turn the same in a counter-clockwise direction and to retain the member in the dotted line position shown in Fig. 6, whenever the driving member 67 is displaced from its stand-by or inoperative position, that is to say, when the latch member 85 rides upon the cam 159 during the entire record changing cycle of movement of the member 67 and until just before the member returns to stand-by or inoperative position. So long as the member 85 is in the dotted line position shown in Fig. 6, the member 45 is free to swing against the stop 145 and occupy a position wherein the pin 153 may engage one or other of the stop shoulders 151. As the member 67 approaches and reaches its stand-by position, the member 85, riding on the cam 159 under the influence of the spring 89, will return to the solid line position shown in Fig. 6, thereby retracting the member 145 against the influence of the spring 147 by the action of the pin 157 on the shoulder 155, thus releasing the arm 45 and the tone arm connected therewith for playing movement. As the member 67 reaches its stand-by position thereby releasing the tone arm for

playing movement, the cam 83 is also retracted from beneath the pin 53 thereby lowering the tone arm upon the record in position to commence the playing of the same.

The driving member 67, of course, in returning to its stand-by position, from the position shown in Fig. 5, through the action of the connecting rod 66, will restore the record changing blades to the normal stack supporting position shown in Figs. 1 and 3. It is desirable to provide means for latching the record changing mechanism in position with the blades 33 supporting the stack and also in record changing position with the blades 35 supporting the stack. To this end, the connecting bar 63 may be provided with spaced notches 161 and 162, and a spring pressed latch member 163 pivoted as at 165 on the plate 13 may also be provided. The latch member has a tongue 167 adapted to engage the notch 161 when the record changing mechanism is in shifted position with the blades 35 supporting the record stack and to latchingly engage the notch 162 when the record changing mechanism is in normal position with the blades 33 supporting the record stack. The latch 163 has a portion extending adjacent an edge of the slot 105' in position to be engaged by the bushing 101 of the driving device 93' as the same travels the slot 105' in either direction so as to release the latch from the notch 162 while the member 67 is traveling from the position shown in Fig. 4 to the position shown in Fig. 5 of the drawings, and thereby release the record changing mechanism for operation.

The latch 163 is likewise released from latching engagement in the notch 161 during the return movement of the member 67 from the position shown in Fig. 5 to the position shown in Fig. 4 of the drawings, to thereby release the record changing mechanism for actuation by the continued movement of the member 67.

In order to control the adjustable stop 149 and also to provide means for tripping the latch 111 manually at any time during the playing of a record, in order to thus reject the record being played and to substitute another record by operation of the change mechanism, we provide a single manually operable control, which is shown more particularly in Figs. 9, 10 and 11. This control comprises a support frame 169 (see Fig. 10) clampingly secured in a suitable opening in the plate 13 by the nut 172. This support frame forms a bushing for supporting a tubular member having a disc 171 presented at the end of the bushing 169 beneath the plate 13. The other end of the tubular member projects upwardly of the bushing and carries a manually operable knob 173 exposed upwardly of the plate 13. The adjustable stop 149 comprises a bent lug of an elongated member 175, which is slidably secured to the underside of the plate 13 by any suitable retaining means. To this end the stop member 149 may be used by forming the same as a headed pin extending through a slot 177 in the member 175 to thereby retain the same slidably on the plate 13. The other end of the member 175 is connected with the disc 171 as by means of a stud 179. By turning the knob 173, the member 175 may be shifted in order to present the stop member 149 in adjusted position to determine the position occupied by the member 145 and hence by the shoulders 151 thereof, under the influence of the spring 147, when the member 85 is turned by the action of the cam 159. The position of the member 145 thus determines the starting posi-

tion to which the tone arm may be turned in applying the same on a record to be played. Consequently, it is necessary to provide for as many adjusted positions of the knob 173 as there are stop shoulders 151 on the member 145. We prefer also to provide an adjusted knob position in which the stop member 149 prevents all of the shoulders 151 from being projected into position to engage the pin 153. We also provide a latch 181 pivoted on the bottom of the plate 13, as by means of the stud 183, said latch being preferably spring urged in a direction to engage the spring pressed head of the stud 95 of the driving device 93. The latch 181 is operatively connected with the member 175, however, and is so arranged that the latch will lock the member 93 against operation when the stop 149 is in position preventing engagement of the shoulders 151 with the position determining pin 153. When in such position, the record playing equipment will be permitted to function as if the record changing mechanism was non-existent thereby conditioning the apparatus for manual operation. The latch 181, however, will be retracted from the driving device 93 leaving the same cocked for action upon operation of the latch lever 111 thereby rendering the apparatus automatically operative whenever the knob is positioned to allow the shoulders 151 to engage the pin 153.

The sleeve member 171 of the control device supports an axial pin 185 having an end extending centrally and upwardly of the knob 173 and carrying a button head 187. The pin 185 has an end extending below the disc 171 in position to engage the arm 199 of a lever 191, which is pivoted as at 193, on the collar 169 beneath the plate 13. By pressing the button 187, the pin 185 may turn the lever 191 on its pivot to move a rod 195. This rod 195 is slidably supported in a guide 197 and has an end 199 hooked around the end of the latch releasing lever 125 so that by pressing on the button 187 the latch 111 may be tripped, thereby initiating the record changing cycle of the device.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

Having thus described the invention, what we claim as new and desire to secure by Letters Patent of the United States is:

1. Phonographic apparatus comprising the combination, with a record turntable, a motor for turning the same and a tone arm movable with respect to the turntable, of record changing means comprising a driving member normally retained in stand-by position, normally inoperative driving means connectible with the motor to move the member in one direction to a projected position, said driving means being connectible with said motor when the member is in projected position to return the member to stand-by position, means driven by said member for swinging the tone arm radially with respect to said turntable and for raising and lowering the tone arm with respect to the turntable, record changing mechanism driven by said member, and releasing means operable by said tone arm, as at the conclusion of the playing of a record on the turntable, to actuate said driving means, said

releasing means comprising a lever having teeth formed along an arm thereof, a tooth member pivoted on and swingable with said tone arm, said tooth being yieldable on the pivot to tilt thereon and thereby engage said teeth and pass over them draginely in ratchet fashion without tilting the lever, so long as the tone arm moves continuously in one direction during the playing of a record, said tooth being adapted to straighten itself on its pivot by the locking of its tip between a pair of said teeth and thereby move said lever to release said driving means upon reversal of record playing movement of the tone arm, as when the same enters an eccentric record groove.

2. Phonographic apparatus comprising a combination of, a record turntable, means operatively associated with the turntable for turning the same, record changing means, driving means comprising a cam formed on the underside of the turntable, clutch means drivingly connecting said record changing means with said cam driving means, and means operatively connected to said clutch means to render said clutch means operative.

3. Phonographic apparatus comprising a combination of, a record turntable, means operatively associated with the turntable for turning the same, record changing means, driving means comprising means forming a spiral groove in the underside of the turntable, clutch means drivingly connecting said record changing means with said spiral groove, and means operatively connected to said clutch means to render said clutch means operative.

4. Phonographic apparatus comprising a combination of, a record turntable, means operatively associated with the turntable for turning the same, record changing means, driving means formed on the underside of the turntable, an actuating member operatively associated with said record changing means, a plurality of clutch means successively drivingly connecting said actuating member with said driving means, at least one of said clutch means being operative to connect said actuating member with said driving means to move said actuating member to a predetermined position to operate said record changing means and another of said clutch means being operative to connect said actuating member to said driving means to restore said actuating member to its initial position, and means operatively connected to said clutch means selectively to render said clutch means operative.

5. Phonographic apparatus comprising a combination of, a record turntable, means operatively associated with the turntable for turning the same, record changing means, driving means comprising means forming a cam groove on the underside of the turntable, clutch means comprising a clutch pin, means operatively associated with said clutch pin and with said record changing means to drivingly connect said clutch pin with said cam groove, and means operatively associated with said clutch pin to hold it out of engagement with said driving means during the playing of a record.

6. Phonographic apparatus comprising a combination of, a record turntable, means operatively associated with the turntable for turning the same, record changing means, driving means comprising means forming a spiral groove on the underside of the turntable, clutch means drivingly connecting said record changing means with said spiral groove, means operatively connected to said clutch means to render said clutch means opera-

tive, and means associated with said spiral groove to disconnect said clutch means from said driving connection with said spiral groove.

5 7. Phonographic apparatus comprising a combination of, a record turntable, means operatively associated with the turntable for turning the same, a tone arm associated therewith pivoted for vertical and horizontal movement, record changing means, driving means comprising a cam formed on the underside of the turntable, clutch means drivingly connecting said record changing means and said tone arm with said cam, and means operatively connected to said clutch means to render said clutch means operative.

15 8. Phonographic apparatus comprising a combination of, a record turntable, means operatively associated with the turntable for turning the same, a tone arm associated therewith pivotally mounted for vertical and horizontal movement, record changing means, driving means formed on the underside of the turntable, actuating means operatively associated with said record changing means comprising clutch means drivingly connecting said record changing means with said driving means, slip clutch means drivingly connecting said actuating means with said tone arm to move the tone arm to a standby position during a record changing operation and then back to playing position, and means operatively connected to said first clutch means to render said clutch means operative.

25 9. Phonographic apparatus comprising a combination of, a record turntable, means operatively associated with the turntable for turning the same, a tone arm associated therewith pivoted for vertical and horizontal movement, record changing means, driving means comprising a cam formed on the underside of the turntable, actuating means operatively associated with said record changing means and provided with clutch means drivingly connecting said record changing means with said driving means, a cam member associated with said actuating means and operatively associated with the tone arm to cause 35 the tone arm to ascend and descend at predetermined times before and after the changing of a record, another cam member associated with said actuating means and operatively associated with the tone arm to cause the tone arm to be rotated horizontally, and means operatively connected to said clutch means to render said clutch means operative.

40 10. Phonographic apparatus comprising a combination of, a record turntable, means operatively associated with the turntable for turning the same, a tone arm associated therewith pivoted for vertical and horizontal movement, record changing means, driving means formed on the underside of the turntable, actuating means 45 operatively associated with said record changing means and provided with clutch means drivingly connecting said record changing means with said driving means, means operatively associated with said actuating means and with said tone arm to cause said tone arm to pivot vertically prior to a record changing operation, to pivot horizontally to a standby position during the record changing operation, to return to playing position and to descend on the record, adjustable stop means 50 operable to stop the movement of the tone arm from the standby position to the playing position at a predetermined point depending upon the size of the record to be played, means associated with said actuating means to release the stop means when the tone arm descends on a record,

means operatively connected to said clutch means to render said clutch means operative, and means operatively associated with said driving means to disengage said clutch means from said driving means.

11. Phonographic apparatus comprising a combination of, a record turntable freely mounted on a base plate, a motor drivingly connected to the turntable for turning the same, means forming a spiral groove on the underside of the turntable, an actuating member pivotally mounted beneath said base plate, a pair of spaced clutch means each comprising a pin mounted on said actuating member in spaced relation to each other and to the pivot point of the actuating member operable to move upwardly through an opening in said base plate to engage said spiral groove, means operatively associated with each of said clutch pins to prevent said upward movement during the playing of a record, means operatively associated with one of said clutch means to render its clutch pin operative to engage said spiral groove while the other clutch pin is held out of engagement with the spiral groove, means operatively associated with said first clutch pin to move it out of operative engagement with said spiral groove as it reaches a predetermined point in the latter, means operatively associated with the other clutch means to render its associated clutch pin operative to engage the spiral groove when the first clutch pin is withdrawn therefrom, means operatively associated with said second clutch means to move said second clutch pin out of engagement with said spiral groove as it reaches a predetermined point in the latter, record changing means, and means drivingly connecting said actuating member to said record changing means to cause a record to be disposed on the turntable during the period that said first clutch pin is operatively engaged in said spiral groove.

12. Phonographic apparatus comprising a combination of, a record turntable freely mounted on a base plate, a motor drivingly connected to the turntable for turning the same, a tone arm associated therewith pivoted for vertical and horizontal movement, means forming a spiral groove on the underside of the turntable, an actuating member pivotally mounted for horizontal movement beneath said base plate, a pair of spaced clutch means each comprising a pin mounted on said actuating member in spaced relation to each other and to the pivot point of the actuating member operable to move upwardly through an opening in said base plate to engage said spiral groove, means operatively associated with each of said clutch pins to prevent said upward movement during the playing of a record, means operatively associated with one of said clutch means to render its clutch pin operative to engage said spiral groove while the other clutch pin is held out of engagement with the spiral groove, means operatively associated with said first clutch pin to move it out of operative engagement with the spiral groove as it reaches a predetermined point in the latter, means operatively associated with the other clutch means to render its associated clutch pin operative to engage the spiral groove when the first clutch pin is withdrawn therefrom, means operatively associated with said second clutch means to move said second clutch pin out of engagement with said spiral groove as it reaches a predetermined point in the latter, record changing means, means drivingly connecting said actuating member to said record chang-

ing means to cause a record to be disposed on the turntable during the period that said first clutch pin is operatively engaged in said spiral groove, an arm having an arcuate shaped end fixed to

5 rotate with said actuating member, a cam plate fixed to rotate with said actuating member, a cam track on said plate having a lower and a raised portion, a pin engaging said cam track at one end and said tone arm at the other end to raise 10 the tone arm when said pin ascends on said raised portion and to lower it when it descends as in playing a record, and a friction wheel engaging the edge of said arcuate shaped end of said arm operable to rotate the tone arm horizontally, said wheel rotating the tone arm off of the turntable to a standby position when the first clutch pin is engaged in said spiral groove and rotating it back to playing position when the second clutch pin is engaged.

13. Phonographic apparatus comprising a combination of, a record turntable freely mounted on a base plate, a motor drivingly connected to a turntable for turning the same, a tone arm associated therewith pivoted for vertical and horizontal movement, means forming a spiral groove on the underside of the turntable, an actuating member pivotally mounted beneath said base plate, a pair of spaced clutch means each comprising a pin mounted on said actuating member in spaced relation to each other and to the pivot point of the actuating member operable to move upwardly through an opening in said base to engage said spiral groove, means operatively associated with each of said clutch pins to prevent said upward movement during the playing of a record, means operatively associated with one of said clutch means to render its clutch pin operative to engage said spiral groove while the other clutch pin is held out of engagement with the spiral groove, means operatively associated with said first clutch pin to move it out of operative engagement with the spiral groove as it reaches a predetermined point in the latter, means operatively associated with the other clutch means to render its associated clutch pin operative to engage the spiral groove when the first clutch pin is withdrawn therefrom, means operatively associated with said second clutch means to move said second clutch pin out of engagement with said spiral groove as it reaches a predetermined point in the latter, record changing means, means drivingly connecting said actuating member to said record changing means to cause a record to be disposed on the turntable during the period that said first clutch pin is operatively engaged in said spiral groove, an arm having an arcuate shaped end fixed to rotate with said actuating member, a cam plate fixed to rotate with said actuating member, a cam track on said plate having a lower and a raised portion, a pin engaging said cam track at one end and said tone arm at the other end to raise the tone arm when said pin ascends on said raised portion and to lower it when it descends as in playing a record, a friction wheel

55 engaging the edge of said arcuate shaped end of said arm operable to rotate the tone arm horizontally, said wheel rotating the tone arm off of the turntable to a standby position when the first clutch pin is engaged in said spiral groove and rotating it back to playing position when the second clutch pin is engaged, adjustable stop means mounted on said base plate and operatively associated with said tone arm to stop the inward movement of the tone arm at a predetermined

playing position, and release means operatively associated with said actuating member and with said stop means to release said stop means when the tone arm descends on the record.

14. Phonographic apparatus comprising a combination of, a record turntable freely mounted on a base plate having holes therein, a motor drivingly connected to the turntable for turning the same, means forming a spiral groove on the underside of the turntable, an actuating member pivoted beneath said base plate, a pair of spaced clutch means each comprising a spring pressed pin mounted on said actuating member in spaced relation to each other and to the pivot point of the actuating member operable to move upwardly through said holes under the influence of its associated spring to engage said spiral groove, latch means operatively associated with each of said clutch pins to prevent said upward movement during the playing of a record, delatching means operatively associated with one of said clutch means to render its clutch pin operative to engage said spiral groove while the other pin is held out of engagement with the spiral groove, said delatching means comprising at least one of the following: (a) a manually actuated lever operatively associated with said latching means of said first clutch pin, (b) a lever operatively associated with the tone arm and the latching means of said first clutch pin operative to delatch said first clutch pin when the tone arm reaches a predetermined position, and (c) a lever operatively associated with the tone arm and the latching means of said first clutch pin operative to delatch said first clutch pin upon eccentric movement of the tone arm, means operatively associated with said first clutch pin to move it out of operative engagement with the spiral groove as it reaches a predetermined point in the latter, means operatively associated with the other clutch means to render its associated clutch pin operative to engage the spiral groove when the first clutch pin is withdrawn therefrom, means operatively associated with said second clutch means to move said second clutch pin out of engagement with said spiral groove as it reaches a predetermined point in the latter, record changing means, and means drivingly connecting said actuating member to said record changing means to cause a record to be disposed on the turntable during the period that said first clutch pin is operatively engaged in said spiral groove.

15. Phonographic apparatus comprising a combination of, a record turntable freely mounted on a base plate having slots therein, a motor drivingly connected to the turntable for turning the

same, a tone arm associated therewith pivoted for vertical and horizontal movement, means forming a spiral groove on the underside of the turntable, an actuating member pivotally mounted beneath said base plate, a pair of spaced clutch means each comprising a spring pressed pin mounted on said actuating member in spaced relation to each other and to the pivot point of the actuating member operable to move upwardly through said slots to engage said spiral groove, means associated with said actuating member and the sides of said slots to support said actuating member, latch means operatively associated with each of said clutch pins to prevent said upward movement during the playing of a record, detaching means operatively associated with one of said clutch means to render its clutch pin operative to engage said spiral groove while the other clutch pin is held out of engagement with the spiral groove, means operatively associated with said first clutch pin and with said spiral groove to move the pin out of operative engagement with the spiral groove as it reaches the inner end of the latter, means operatively associated with the other clutch means to render its associated clutch pin operative to engage the spiral groove when the first clutch pin is withdrawn therefrom, means operatively associated with said second clutch means and said spiral groove to move said second clutch pin out of engagement with said spiral groove as it reaches the inner end of the latter, record changing means, means drivingly connecting said actuating member to said record changing means to cause a record to be disposed on the turntable during the period that said first clutch pin is operatively engaged in said spiral groove, a member having an arcuate shaped end fixed to rotate with said actuating member, a cam plate fixed to rotate with said actuating member, a cam track on said plate having a lower and a raised portion, a pin engaging said cam track at one end and said tone arm at the other end to raise the tone arm when said pin ascends on said raised portion and to lower it when it descends as in playing a record, and slip clutch means comprising a friction wheel engaging the edge of said arcuate shaped end operable to rotate the tone arm horizontally, said wheel rotating the tone arm off of the turntable to a standby position when the first clutch pin is engaged in said spiral groove and rotating it back to playing position when the second clutch pin is engaged.

Certificate of Correction

Patent No. 2,394,539.

February 12, 1946.

JOSEPH ERWOOD ET AL.

It is hereby certified that errors appear in the printed specification of the above numbered patent requiring correction as follows: Page 2, second column, line 54, for "substantially" read *substantially*; page 3, second column, line 9, for "mean" read *means*; line 37, for "turntable" read *turnable*; line 58, for "to stand-by" read *the stand-by*; page 9, second column, line 16, claim 15, for "detaching" read *detaching*; and that the said Letters Patent should be read with these corrections therein that the same may conform to the record of the case in the Patent Office.

Signed and sealed this 21st day of May, A. D. 1946.
